SEWING MACHINE

Andrew B. Clayton, Elizabeth, N. J., assignor to
The Singer Manufacturing Company, Elizabeth, N. J., a corporation of New Jersey

Application July 23, 1946, Serial No. 685,725

12 Claims. (Cl. 112—258)

1

This invention relates to sewing machines and more particularly to sewing machines of the so-called "family" or "domestic" type.

A primary object of the present invention is to render available a relatively small, lightweight, easy running sewing machine adapted to be used selectively for performing any one of a plurality of unlike sewing operations, such, for example, plain sewing on flat work, the closure of tubular elements, such as sleeves and legs of articles of wearing apparel, and darning and embroidering on either flat or tubular work.

Another object of the invention is to provide an improved base member for a sewing machine of this nature which is designed to present to the user, selectively, either a flat work-supporting member of relatively large dimensions for flat work or a relatively small cylindrical work-supporting member for tubular work.

Another object is to provide an improved base member for a convertible sewing machine as above described and to embody in said base member improved work-feeding and loop-taking mechanisms capable of being actuated from driving means located within a conventional sewing machine bracket-arm removably secured upon the improved base member.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings:

Fig. 1 is a vertical sectional view of a sewing machine embodying the present invention.

Fig. 2 is a bottom view thereof with a portion of a removable work-supporting plate broken away.

Fig. 3 is a left end view of the machine illustrated in Fig. 1 with the base thereof shown in section better to disclose the work-feeding mechanism and with the face-plate and the bracket-arm head removed to disclose the parts within said head.

Fig. 4 is a vertical section taken on the lines 4—4 of Figs. 2 and 3.

Fig. 5 is a horizontal section taken substantially on the line 5—5 of Fig. 1, illustrating the means for supporting and rotating the loop-taker.

Fig. 6 is a detail sectional view illustrating, in 55

2

full and dotted lines, the means for giving to the feed-bar its feed and return movements.

Fig. 7 is a detail sectional view illustrating, in full and dotted lines, the means for giving to the feed-bar its rising and falling movements.

Fig. 8 is a detail perspective view of the rear end of the feed-bar and the rock-arms which give to the feed-bar its horizontal and vertical movements.

10 Referring more specifically to the drawings, the invention is disclosed as embodied in a sewing machine comprising a base B of generally U-shape in plan view. One leg 1^a and the cross-bar 1^b of the U-shaped base are of inverted box-like form, whereas the other leg 1^c is of substantially cylindrical form. While the portion 1^c of the base B is not truly "cylindrical," as shown by Fig. 1, for convenience that term will be used hereinafter as describing the shape of that portion of the base. It is to be understood that, as used in this specification, the term "cylindrical" is intended to mean the shape shown in the drawings or any generally similar shape such as may be used satisfactorily as a work-supporting horn.

15 Secured upon the upper surface of the portion 1^a of the base, as by screws 2, of which only one is shown, is the standard 3 of a sewing machine bracket-arm A including an overhanging arm 4 which terminates at its free end in a hollow bracket-arm head 5. Journaled lengthwise within the arm 4, in bearings 6, is a main or drive shaft 7 carrying at its rear end, a combined belt and hand wheel 8 which may be rotated from any suitable source of power, such, for example, as an electric motor M, through the medium of a belt C. The bracket-arm and the mechanisms carried thereby are of conventional form, being substantially the same as those disclosed in United States patents of H. J. Goosman, No. 2,031,562,

20 Feb. 18, 1936, and No. 2,063,841, Dec. 8, 1936. Stated briefly, the mechanism within the bracket-arm comprises a needle-bar 9 mounted for reciprocation in bearings 10 in the bracket-arm head 5 and driven from a crank disk 11, on the shaft 7, by a link 12. At its lower end the needle-bar carries an eye-pointed needle 13 forming a part of a stitch-forming mechanism. Also mounted in the head 5 is a spring-depressed presser-bar 14 carrying, at its lower end, a 25 presser-foot 15. A thread take-up device 16 also is located mainly within the head 5 and is operated from the crank-disk 11.

30 Fixed upon the drive shaft 7 is a bevel gear 17 which serves as the initial driving element of a loop-taker driving train. The gear 17 meshes

with and drives a bevel gear 18 secured upon the upper end of a vertical shaft 19 journaled in bearings 20 in the standard 3. At its lower end, the shaft 19 carries a bevel gear 21 which drives a bevel gear 22 secured upon one end of a shaft 23 journaled in bearings 23^a in the base B. As viewed in plan from the front of the machine, the shaft 23 extends rearwardly and diagonally to the left so that the axis a of the shaft intersects the axis b of a loop-taker shaft 24 (Fig. 5) journaled in bearings 25 in the forwardly extending cylindrical portion 1^c of the machine base. The shaft 23 has secured to its rear end a bevel gear 26 which meshes with and drives a similar gear 27 secured upon the loop-taker shaft 24. A loop-taker 28, fixed upon the shaft 24, cooperates with the needle 13 in the formation of stitches. The ratios of the gears 17—18, 21—22, and 26—27 are such that the shaft 24 and the loop-taker carried thereby are given two rotations for each single rotation of the drive shaft 7, as is common in lock-stitch sewing machines.

Cooperating with the presser-foot 15, in the feeding of the work, is a four motioned work-feeding mechanism comprising a serrated feed-dog 29 secured upon the forward end of an endwise and vertically movable feed-bar 30 slidably fulcrumed on a stud 31 secured in a lug 32 depending from the underside of the upper wall of the cylindrical portion 1^c of the machine base. The serrated portions of the feed-dog operate through slots 33 in a throat-plate 34 secured upon the free end portion of the cylindrical frame element 1^c.

The feed-bar 30 and the feed-dog 29 carried thereby are given their forward and backward or feed and return movements from a cam 35 secured upon the shaft 7 through mechanism comprising an oscillating and endwise movable lever 36, pivoted, at 37, to an arm 38 projecting substantially horizontally from an auxiliary feed-drive rocker 39 journaled in the portion 1^a of the base B on pintles 40. The lever 36 is formed with a forked upper end 36^a which straddles and engages the cam 35. Thus rotation of the shaft 7 and cam 35 effect oscillatory movements of the lever 36 about its pivot 37. These oscillatory movements are translated into endwise movements of the lever by the action of a roller stud 41 carried by the lever and tracking the walls of a slot 42 formed in a tiltable block 43 pivotally secured to the standard 3 by a screw 44. A hand lever 45 connected to the block 43 affords means for tilting the block to vary the amplitude and direction of movement of the lever 36 and consequently the amplitude and direction of movement of the feed-dog 29.

The auxiliary feed-drive rocker 39 also carries an upstanding arm 46 to which is pivotally connected, at 46^a, one end of a link 47, the other end of which is pivotally connected at 48, to an arm 49 depending from adjacent the rear end of a main feed-drive rocker 50, journaled on pintles 51 in the base B. At its front end the feed-drive rocker 50 provides an upstanding arm 52, carrying a stud 53, which fits into a vertically disposed slot 54 formed in the enlarged rear end portion 30^a of the feed-bar 30. From the foregoing it will be understood that rotation of the drive shaft 7 effects endwise reciprocation of the feed-bar 30 and the feed-dog 29 carried thereby.

Likewise, rotation of the shaft 7 effects oscillatory movements of the feed-bar about its fulcrum 31 to give to the feed-dog its rising and falling movements. This is effected from an

eccentric 55 secured upon the shaft 7 adjacent the cam 35. This eccentric is embraced by a strap 56 formed at the upper end of a pitman 57 which is pivotally connected, at its lower end, by a screw 58 to a substantially horizontal arm 59 forming a part of an auxiliary feed-lift rocker 60 journaled, on pintles 61, in the portion 1^a of the base B. The auxiliary rocker 60 is also provided with an upwardly extending arm 62 to which is pivotally connected, by a screw 63, the forward end of a link 64, the rear end of which is pivoted, by a screw 65, to a downwardly extending arm 66 forming a part of a main feed-lift rocker 67. The forward end portion of the rocker 67 is reduced, as at 67^a, and is journaled in a bearing bushing 68 supported by a boss 69 formed integrally with the base B. For convenience of assembly the rear end portion 67^b of the main feed-lift rocker 67 is journaled upon a rod 70 secured in the machine base. Secured to the reduced portion 67^a of the feed-lift rocker at one end of the bearing bushing 68 is the hub portion 71^a of a feed-lift rock-arm 71 which carries a stud 72 fitted into a slot 73 in the rear end portion of the feed-bar 30. A thrust collar 74 secured upon the portion 67^a of the feed-lift rocker 67 cooperates with the bushing 68, boss 69 and hub 71^a to prevent endwise movement of the feed-lift rocker. From the foregoing it will be understood that rotation of the shaft 7 effects vertical oscillation of the feed-bar 30, thus giving to the feed-dog 29 its rising and falling movements in timed relation with its forward and backward reciprocations, as is common in four-motion work-feeding mechanisms of sewing machines.

As hereinbefore stated an object of this invention is to provide a sewing machine which selectively may be used for various types of sewing operations. To that end the generally U-shaped base B is adapted to have removably secured thereto a relatively large sheet metal work-supporting plate 75 which covers a part of the base portion 1^a and the entire portions 1^b and 1^c to adapt the machine for plain sewing on flat work. The plate 75 may be held in place by dowel pins 76 carried thereby entering dowel holes 77 in the base B and by a substantially U-shaped clamp, or stirrup 78, secured to the underside of the plate 75 and embracing the cylindrical portion 1^c of the bed. The stirrup 78 carries a thumb-screw 79 designed to be adjusted into contact with the underside of the cylindrical bed portion 1^c, thereby to draw the work-plate 75 into firm contact with the upper face of the bed B. The work-plate 75 is formed with an aperture 80 which receives the throat-plate 34.

When it is desired to sew tubular work the thumb screw 79 may be released and the work-supporting plate 75 may be entirely removed from the machine, thus leaving the cylindrical portion 1^c of the bed as the work-supporting element.

The above described machine may also be adapted for darning and embroidering operations and the like on either flat or tubular work either by securing to the cylindrical work-supporting arm a specially formed throat-plate having a needle-hole and a raised portion which overlies the feed-dog and prevents it from engaging the work while continuing its normal work feeding motions, as shown in United States patent of G. M. Eames, No. 2,024,435, Dec. 17, 1935, or by securing to the machine, above the throat-plate, a feed cover-plate of any suitable or pre-ferred form, such, for example as a feed-cover

plate of the type illustrated in United States patent of Stafford, No. 937,112, Oct. 19, 1909.

From the foregoing it will be perceived that I have provided an improved sewing machine capable of performing both plain sewing and darning or like operations on either flat or tubular work, including the closing of tubular articles. Furthermore it will be apparent that I have provided improved means for operating a four-motioned feed mechanism embodied in a cylindrical work-supporting arm from a rotary shaft in the sewing machine bracket-arm, and also improved means for rotating a loop-taker in a cylindrical arm sewing machine.

Having thus set forth the nature of the invention, what I claim herein is:

1. A sewing machine comprising a generally U-shaped base, one portion of which is of inverted box-like form and another portion of which is arranged substantially parallel to the first mentioned portion and is of cylindrical form, a bracket-arm secured upon said base, a rotary drive shaft journaled in said bracket-arm transversely of the axis of the cylindrical portion of the frame, a reciprocating needle-bar carried by said bracket-arm and actuated from said drive shaft, an eye-pointed needle carried by said needle-bar, a rotary loop-taker journaled in the cylindrical portion of said base transversely of said drive shaft and cooperating with said needle in the formation of stitches, a four-motioned work-feeding mechanism mounted in the cylindrical portion of said base, and means actuated from said rotary drive shaft and extending through said portions of said base for rotating said loop-taker and for operating said four-motioned work-feeding mechanism.

2. A sewing machine comprising an integrally formed, generally U-shaped base, one portion of which is of inverted box-like form and another portion of which is of cylindrical form and constitutes a work-supporting horn, an integrally formed bracket-arm secured upon said base with its longitudinal axis arranged transversely of the axis of the cylindrical portion of the base, a rotary drive shaft journaled lengthwise in said bracket-arm, a reciprocating needle-bar mounted in said bracket-arm and actuated from said drive shaft, an eye-pointed needle carried by said needle-bar, a rotary loop-taker shaft journaled lengthwise of said work-supporting horn, a loop-taker secured upon the loop-taker shaft and cooperating with said needle in the formation of stitches, a work-feeding mechanism including an oscillatory and endwise movable feed-bar located in said work-supporting horn, a serrated feed-dog carried by said feed-bar, means for giving to said loop-taker shaft a plurality of rotations from a single rotation of said drive shaft, and means actuated from said drive shaft for oscillating and reciprocating said feed-bar.

3. A sewing machine comprising an integrally formed generally U-shaped base, one portion of which is of cylindrical form and constitutes a work-supporting horn having a relatively small work-supporting surface, a bracket-arm secured upon said base with its longitudinal axis arranged transversely of the cylindrical portion of the base, a rotary drive shaft journaled lengthwise in said bracket-arm, a reciprocating needle-bar carried by said bracket-arm and actuated from said drive shaft, an eye-pointed needle carried by said needle-bar, a rotary loop-taker journaled in said horn and cooperating with said needle in the formation of stitches, a four-mo-

tioned work-feeding mechanism mounted in said horn and adapted to feed work lengthwise of the horn, means for operating said loop-taker and said work-feeding mechanism from said drive shaft, and a substantially rectangular work-supporting plate removably secured upon said base and overlying said work-supporting horn and providing a work-supporting surface of relatively large area.

10 4. A sewing machine comprising an integrally formed generally U-shaped base, one portion of which is of box-like form and another portion of which is of cylindrical form, a bracket-arm secured upon said box-like portion with its longitudinal axis arranged transversely of the cylindrical portion of the base and having a bracket-arm head overhanging one end of said cylindrical portion, a rotary loop-taker mounted in said cylindrical portion, a reciprocating needle-bar carrying an eye-pointed needle mounted in said head, said needle cooperating with said loop-taker in the formation of stitches, a drive shaft journaled in said bracket-arm, means driven from said shaft for actuating said needle-bar and loop-taker, and a substantially rectangular work-supporting plate adapted to be removably secured upon said base and to overlie said cylindrical portion to convert the machine from a horn-bed machine to a flat-bed machine.

15 5. A sewing machine comprising a base, one portion of which is of box-like form and another portion of which is of cylindrical form and which projects forwardly from the rear portion of the base, a loop-taking mechanism located in said cylindrical portion and comprising a rotary loop-taker shaft journaled lengthwise thereof and a loop-taker secured upon the forward end of said shaft, a bracket-arm secured upon said base, a horizontally disposed drive-shaft journaled in said bracket-arm, a third shaft journaled vertically in said bracket-arm, a gear connection between said drive shaft and said third shaft, a fourth shaft journaled in said base with its axis intersecting the axes of said third shaft and said loop-taker shaft, and bevel gear connections between said third shaft and said fourth shaft and between said fourth shaft and said loop-taker shaft.

20 6. A sewing machine comprising a substantially U-shaped base, one portion of which is of box-like form and another portion of which projects forwardly from said box-like portion and is of cylindrical form, a rotary loop-taker shaft journaled lengthwise within said cylindrical portion, a loop-taker secured upon the forward end of said loop-taker shaft, a bracket-arm secured upon said base, a horizontally disposed drive shaft journaled in said bracket-arm, a third shaft journaled vertically in said bracket-arm, a bevel gear connection between said drive shaft and said third shaft, a fourth shaft journaled horizontally and diagonally in the box-like portion of said base with its axis intersecting the axes of said third shaft and said loop-taker shaft, and bevel gear connections between said third shaft and said fourth shaft and between said fourth shaft and said loop-taker shaft.

25 7. A sewing machine comprising a generally U-shaped base one portion of which is of box-like form and another portion of which is of cylindrical form, a bracket-arm secured upon said base with its longitudinal axis transverse to the longitudinal axis of the cylindrical portion of said base, a drive shaft journaled lengthwise within said bracket-arm, an auxiliary feed-drive rocker jour-

naled in the box-like portion of said base, means for actuating said rocker from said drive shaft, a main feed-drive rocker journaled in said base with its axis substantially parallel to said axis of the bracket-arm, a link connection between said feed-rockers, a feed-bar pivotally and slidingly mounted in the cylindrical portion of said base, a feed-dog carried by said feed-bar, and means actuated by said main feed-drive rocker for giving reciprocatory movements to said feed-bar.

8. A sewing machine comprising a generally U-shaped base, one portion of which is of box-like form and another portion of which is of cylindrical form, a bracket-arm secured upon said base with its longitudinal axis transverse to the longitudinal axis of the cylindrical portion of said base, a drive shaft journaled lengthwise within said bracket-arm, an auxiliary feed-lift rocker journaled in the box-like portion of said base, means for actuating said rocker from said drive shaft, a main feed-lift rocker journaled in said base with its axis substantially parallel to said axis of the bracket-arm, a link connection between said feed-rockers, a feed-bar pivotally and slidingly mounted in the cylindrical portion of said base, a feed-dog carried by said feed-bar, and means actuated by said main feed-lift rocker for giving oscillatory movements to said feed-bar.

9. A sewing machine comprising a generally U-shaped base, one portion of which is of box-like form and another portion of which is of cylindrical form, a bracket-arm secured upon said base with its longitudinal axis transverse to the longitudinal axis of the cylindrical portion of said base, a drive shaft journaled lengthwise within said bracket-arm, an auxiliary feed-drive rocker and an auxiliary feed-lift rocker journaled in the box-like portion of said base, means for actuating said rockers from said drive shaft, a main feed-drive rocker and a main feed-lift rocker journaled in said base with their axes substantially parallel to said axis of the bracket-arm, link connections between said auxiliary and main feed-drive and feed-lift rockers, a feed-bar pivotally and slidingly mounted in the cylindrical portion of said base, a feed-dog carried by said feed-bar, and means actuated by said main feed-rockers for giving reciprocatory and oscillatory movements to said feed-bar.

10. A sewing machine comprising a generally U-shaped base, one portion of which is of box-like form and another portion of which is of cylindrical form, a bracket-arm secured upon said base with its longitudinal axis transverse to the longitudinal axis of the cylindrical portion of said base, a drive shaft journaled lengthwise within said bracket-arm, an auxiliary feed-drive rocker journaled in the box-like portion of said base, means for actuating said rocker from said drive shaft, a main feed-drive rocker journaled in said base and having an upstanding arm, a link connection between said feed-drive rockers, a feed-bar pivotally and slidingly mounted in the cylind-

rical portion of said base, a feed-dog carried by the forward end of said feed-bar, and a pin-and-slot connection between the upstanding arm of said main feed-drive rocker and the rear end of said feed-bar for giving reciprocatory movements to said feed-bar while permitting the feed-bar to be oscillated relative to said main feed-drive rocker.

11. A sewing machine comprising a generally U-shaped base, one portion of which is of box-like form and another portion of which is of cylindrical form, a bracket-arm secured upon said base with its longitudinal axis transverse to the longitudinal axis of the cylindrical portion of said base, a drive shaft journaled lengthwise within said bracket-arm, an auxiliary feed-lift rocker journaled in the box-like portion of said base, means for actuating said rocker from said drive shaft, a main feed-lift rocker journaled in said base and having a horizontally disposed arm, a link connection between said feed-lift rockers, a feed-bar pivotally and slidingly mounted in the cylindrical portion of said base, a feed-dog carried by the forward end of said feed-bar, and a pin-and-slot connection between the horizontally disposed arm of said main feed-lift rocker and the rear end of said feed-bar for giving oscillatory movements to said feed-bar while permitting the feed-bar to be reciprocated relative to said main feed-lift rocker.

12. A sewing machine comprising a generally U-shaped base, one portion of which is of box-like form and another portion of which is of cylindrical form, a bracket-arm secured upon said base with its longitudinal axis transverse to the longitudinal axis of the cylindrical portion of said base, a drive shaft journaled lengthwise within said bracket-arm, an auxiliary feed-drive rocker and an auxiliary feed-lift rocker journaled in the box-like portion of said base, means for actuating said rockers from said drive shaft, a main feed-drive rocker and a main feed-lift rocker journaled in said base, vertical and horizontal arms carried, respectively, by said main feed-drive and feed-lift rockers, operative connections between said auxiliary and main feed-drive and feed-lift rockers, a feed-bar pivotally and slidingly mounted in the cylindrical portion of said base, a feed-dog carried by the forward end of said feed-bar, and pin-and-slot connections between said vertical and horizontal arms and said feed-bar for giving to the feed-bar reciprocatory and oscillatory movements.

ANDREW B. CLAYTON.
